UNITED STATES PATENT OFFICE.

DAVID R. WILSON, OF FENTON, MICHIGAN.

PILLOW-SHAM AND HOLDER.

SPECIFICATION forming part of Letters Patent No. 299,309, dated May 27, 1884.

Application filed April 26, 1883. (No model.)

To all whom it may concern:

Be it known that I, DAVID R. WILSON, of Fenton, in the county of Genesee and State of Michigan, have invented new and useful Improvements in Combined Pillow-Forms and Sham-Holders; and I do hereby declare that the following is a full, clear, and exact description thereof, reference being had to the accompanying drawings, which form a part 10 of this specification.

This invention relates to certain new and useful improvements in the construction and operation of combined pillow-forms and sham-holders; and the invention consists in the peculiar construction, arrangement, and combinations of the various parts, all as more fully hereinafter set forth.

Figure 1 is a perspective view showing my device as attached to the head of a bedstead, 20 with the forms and shams lowered. Fig. 2 is a similar view with the forms elevated.

In the accompanying drawings, which form a part of this specification, A represents the head of a bedstead, to which is secured the 25 rock-bar B, by means of suitable brackets, a, the ends of such bar B being pivotally secured in the brackets.

C represents sham pillows, those shown in the drawings consisting of frames b, provided 30 with raised panels c, said frames being rigidly secured to the rock-bar B. While I show and describe this form of construction, I do not desire to be restricted thereto, as there are various ways in which the desired end can be 35 accomplished, the aim being to provide such a construction as will resemble a pillow, especially when the same is covered by a "sham." The under faces of these "pillow-forms" may be finished perfectly plain, or they may be hand- 40 somely upholstered, so as to present an aesthetic appearance when in their elevated positions.

D represents a fly, the lower edge of which is properly hinged or otherwise secured to the 45 bar B, or to the pillow-forms, as desired, the upper edge of such fly being designed to rest against the head of the bed, to keep the pillow-sham from falling between the frames b and the head of the bed. This fly D may be 50 made of thin board hinged to the pillow-form, or it may be made of leather or other suitable material tacked or otherwise secured to the same, and its free end rests upon a projecting

strip of wood, G, secured to the head of the bedstead. It will of course be understood that 55 this fly is to be so arranged that it will not interfere with the raising of the forms. A ratchet-wheel, E, may be secured upon one end of the bar B, with which a dog, d, engages, and by means of which the inclination of the pillow-forms may be adjusted, as desired, and the pillow forms and shams may be raised and secured against the head of the bed while the latter is being made. Moreover, by the use of the ratchet and dog the frame can be 65 adjusted at any desired height, so as to be laid down over the pillow without actually touching it, and it can be set at just such a height as will allow of the lace of the sham drooping over the edge, and thus displaying the lace to 70 the best advantage, and at the same time hiding the space between the sham and the bed-clothing, which cannot be done in devices of this character where the sham has but two adjustments, as has heretofore been proposed. 75

While I show and describe the employment of a fly above the forms, it is evident that such fly can be dispensed with without departing from the spirit of my invention.

By the employment of a device constructed 80 substantially as described I avoid the necessary use of an extra set of pillows for the purpose of supporting the shams.

What I claim as my invention is—

1. A pillow-sham holder consisting of the 85 pillow-form C, supported on a frame, b, attached to the bar B, in combination with such bar B and means, substantially as described, for holding the forms in any desired position, as and for the purpose set forth. 90

2. The combination of a bedstead, the bar B, pillow-forms C, the frame b, attached to said bar and supporting the forms C, with the brackets a, the ratchet-wheel E, and dog d, as set forth. 95

3. In combination with a bedstead, the bar B, brackets a, pillow-forms C, and shams F, the fly D, resting against a projection on the head of the bedstead, all constructed, arranged, and operating substantially in the manner and 100 for the purposes specified.

DAVID R. WILSON.
